UNITED STATES PATENT OFFICE.

JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

AUTOMOBILE-FENDER.

1,284,374.

Specification of Letters Patent. Patented Nov. 12, 1918.

Application filed February 13, 1915. Serial No. 7,925.

To all whom it may concern:

Be it known that I, JOSEPH LEDWINKA, a citizen of the United States, residing at Philadelphia, in the county of Philadelphia and State of Pennsylvania, have invented new and useful Improvements in Automobile-Fenders, of which the following is a full, clear, concise, and exact description, reference being had to the accompanying drawing, forming a part of this specification.

This invention relates to fenders. It is particularly applicable to fenders for automobiles.

15 Fenders comprise in general a crown and a skirt, which are stamped out of sheet metal, and joined together to form a single structure. Difficulty is experienced in uniting the parts so that the joint between them is rigid and at the same time smooth and finished. As heretofore constructed, a large amount of time and labor has been required for grinding and polishing the joints to give them a proper finish.

20 One of the objects of the present invention is to provide a fender having a smooth and finished joint.

Another object is to provide a light, strong, and durable structure.

25 Another object is to provide a structure which may be readily manufactured.

A further object is to combine a lamp support with a fender, so that the lamp will be rigidly supported and the wires leading thereto thoroughly protected.

30 Other objects and advantages of the invention will hereinafter appear.

In the accompanying drawings, which show a fender embodying the invention—

35 Fig. 1 is a view of a fender in side elevation.

Fig. 2 is a plan view of Fig. 1.

Fig. 3 is a section on the line 3—3 of Fig. 2.

40 Fig. 4 is a view of the transverse section of the joint between the crown and skirt.

Fig. 5 is a perspective of the assembled structure with the crown broken away to show the interior construction.

45 Fig. 6 is a perspective of the supporting arm.

Fig. 7 is a perspective of the lamp bracket. The fender comprises in general a crown

1 and a skirt 2 suitably supported by an arm 3 attached to the side rail 4 of the 55 chassis. A bracket 5 is combined with the fender to form a support for a lamp.

The crown 1 is a sheet metal stamping of suitable shape to guard the wheel of an automobile, and at the same time present a 60 neat, artistic appearance. It is formed with an inturned flange 7, adapted to engage a corresponding flange 6 on the skirt.

The skirt 2 is also stamped from sheet metal. It has an inturned flange 6 adapted 65 to be joined to the flange 7 on the crown, so that the crown and skirt form a unitary fender structure.

The inturned flanges 6 and 7 are generally joined together by welding, preferably 70 by spot welding. The parts may thereby be quickly and efficiently united. By welding the inturned flanges together the parts are united so that the joint between them is not only tight and rigid, but it is finished in 75 appearance. The tedious process of grinding and polishing the joint between the parts is eliminated.

The arm 3 comprises a sheet metal body of channel shape having a flange 8 extending laterally from each side of the top of the channel, an angle bracket 9 one wall 10 of which is spot-welded to the flanges 8 at the lower extremity of the body, and a reinforcing foot 11 which fits over a portion of the 85 lower extremity of the body and is spot-welded thereto, as indicated at 12. The foot 11 has laterally extending flanges 13 which abut bent portions of the flanges 8, and the angle bracket 9 has a projecting wall 14. 90 This construction provides means whereby the arm or bracket 3 may be secured conveniently and rigidly to the side rail 4 of the chassis.

The sheet metal body of the arm 3 is 95 slightly depressed at its inner and lower extremity to accommodate the bracket 9 and the skirt 2 abuts the flanges 8 and extends downwardly over the wall 10 of said bracket. A bead 15 is formed at the edge of the 100 skirt, by shaping the edge around a wire filler 16, presenting a strong and finished construction.

The lamp bracket 5, formed of sheet metal, comprises a base portion 17 provided 105 with rivet holes 18. These rivet holes cor-

respond and are alinable with rivet holes in the skirt 2 and the flanges 8 of the supporting arm, and by a single riveting operation all three members are secured together.

- 5 An aperture 19 is provided in the base 17, whereby the lamp wires may be passed from the channel of the bracket or arm 3 into a conduit 20 formed by the sheet metal lamp bracket 5. In like manner, the side 10 rail 4 is apertured to receive the lamp wires, and the whole construction forms a protective housing.

The supporting arm 3 is shaped to conform with and abut the under side of the 15 crown 1, and also to abut the skirt 2 for a considerable portion of its width. It is particularly shaped to pass across the edges of the inturned flanges 6 and 7. The outer longitudinal side edge of the crown is beaded 20 as at 21, and the outer end 22 of the bracket 3 is downturned to take in over the bead and is spot-welded to the side edge of the crown.

It is to be noted that the skirt 2 is stamped 25 to provide in one piece what is known as the skirt, and the skirt guard, the concave tail portion 23 of the skirt serving as the skirt guard. An upstanding edge 24 of the concave portion extends adjacent the side 30 rail of the chassis and is secured thereto by suitable means.

It will thus be seen that a light, durable and artistic fender has been provided, which is made from a minimum number of parts. 35 These parts are constructed so that they may be quickly, neatly and rigidly joined together, without expending time and energy in grinding and polishing the joint.

The fender support is simple, rigid and 40 efficient. It not only supports the fender but it holds the lamp bracket and forms a conduit for protecting the wires leading to the lamp.

Inasmuch as many changes could be made 45 in the above construction and many widely different embodiments of this invention could be made without departing from the scope thereof, it is intended that all matter contained in the above description or shown 50 in the accompanying drawings shall be considered as illustrative and not in a limiting sense.

What I claim as new and desire to secure by Letters Patent of the United States is:— 55 1. A vehicle fender having, in combination, a crown and a skirt, the contiguous edges of said crown and skirt being provided with inturned abutting flanges which are joined together so that the parts are firmly 60 united by a joint having a smooth exterior.

2. A vehicle fender having, in combination, a crown and a skirt, said parts being formed out of sheet metal and having the contiguous edges thereof provided with in- 65 turned abutting flanges which are welded to-

gether whereby the parts are firmly united by a joint having a smooth exterior.

3. A vehicle fender having, in combination, a crown and a skirt, said parts being formed out of sheet metal and having the 70 contiguous edges thereof provided with in-turned abutting flanges which are spot welded together whereby the parts are firmly united by a joint having a smooth exterior.

4. A vehicle fender having a crown and a 75 skirt, the contiguous edges of said parts being provided with inturned abutting flanges which are joined together, and a supporting arm adapted to be attached to said vehicle frame, said arm being formed to avoid the 80 inturned flanges and to engage the crown and skirt.

5. A vehicle fender having a lamp bracket on the exterior thereof and a supporting arm for the fender adapted to be attached to a 85 vehicle frame, said arm forming a conduit leading to the lamp bracket.

6. A vehicle fender having a lamp bracket on the exterior thereof, said bracket being shaped to form a conduit for wires, and a 90 supporting arm for the fender adapted to be attached to a vehicle frame, said arm forming a conduit communicating with a conduit of the bracket through an opening in the fender. 95

7. A vehicle fender having a sheet metal lamp bracket on the exterior thereof, said bracket being shaped to form a conduit for wires and a pressed metal supporting arm for the fender, said arm being formed with 100 a channel therein the open side of which is inclosed by the under surface of the fender whereby an inclosed conduit is provided, said latter conduit communicating with the former through an opening in the fender. 105

8. A vehicle fender having attached thereto a lamp bracket stamped out of a single sheet of metal, said bracket being adapted to support a lamp casing and to form a conduit for wires leading to the lamp. 110

9. A fender comprising, in combination, a crown and a skirt, said parts being formed out of sheet metal and being provided with abutting inturned flanges, and a supporting arm for said fender having portions thereof 115 engaging said crown and said skirt and united thereto, and other portions adapted to be connected to a vehicle frame.

10. A fender comprising, in combination, a crown and a skirt each of which is formed from sheet metal, the contiguous edges of said crown and skirt being provided with inturned abutting flanges which are welded together and a supporting arm having portions thereof engaging said crown and skirt 120 and united thereto, and other portions thereof adapted to be connected to a vehicle frame. 125

11. A fender comprising, in combination, a crown and a skirt having respectively 130

abutting inturned flanges, a bracket on the top side of said skirt, and a supporting arm engaging the under side of said crown and skirt, said bracket, skirt and supporting arm being securely joined together.

12. A fender, comprising in combination, a sheet-metal crown and a sheet-metal skirt, said crown and skirt having respectively abutting inturned flanges, and a support for 10 said fender comprising a sheet-metal arm formed to avoid the said inturned flanges and engage the crown and the skirt.

13. A fender, comprising in combination, a sheet-metal crown and a sheet-metal skirt, 15 said crown and skirt having respectively abutting inturned flanges, a support for said fender comprising a sheet-metal arm formed to engage the crown and the skirt, and a sheet-metal lamp bracket formed to provide 20 a conduit for wires and comprising a base whereby said bracket may be attached to said skirt.

14. A fender support comprising, in combination, a channel-shaped arm having side 25 flanges adapted to be attached to a fender, and an angle member secured to the flanges of said arm near one end thereof, said angle member having a portion extending substantially at right angles to the flanges at 30 the end of the arm whereby said arm may be readily attached to a rectangular vehicle frame.

15. A fender support comprising, in combination, a channel-shaped body having side 35 flanges, an angle member secured by one wall to said flanges and having another wall extending laterally to provide for fastening means, and a second channel-shaped member fitting over the lower end of said body, 40 secured thereto and provided with a downwardly extending fastening portion.

16. A fender support comprising, in combination, a channel-shaped body having side flanges, an angle member secured by one 45 wall to said flanges and having another wall extending laterally to provide fastening means, and a second channel-shaped member fitting over the lower end of said body, 50 secured thereto and provided with a downwardly extending fastening portion, said angle member being spot-welded to the side flanges of the body and said second channel member being spot-welded to the lower end of said body.

55 17. A vehicle fender having, in combination, a crown and a one-piece skirt, the contiguous edges of said crown and skirt being provided with inturned abutting flanges which are joined together so that the parts 60 are firmly united by a joint having a smooth exterior.

18. A fender comprising, in combination, a crown and a skirt, a bracket on the top side of said skirt, and a supporting arm 65 engaging the underside of said crown and

skirt, said bracket, skirt and supporting arm being securely joined together.

19. A vehicle fender having, in combination, a flanged or channel-shaped crown and a skirt having an inturned flange, said in-turned flange abutting one of the flanges or sides of said channel-shaped crown and being firmly united thereto for the purpose described.

20. In a fender structure, a fender apron 75 and lamp bracket welded together, and a supporting bracket to which said apron is welded, said lamp bracket being opposed to said supporting bracket.

21. In a fender structure, a longitudinally 80 curved fender and a fender apron, said fender and apron having their outer surfaces substantially continuous and having abutting flanges bent away from said outer surfaces and permanently connected together.

22. In a fender structure, a longitudinally curved fender having depending lateral flanges, and a fender apron having its outer surface substantially continuous with that 90 of the fender and having a flange bent away from said outer surface, abutting one of the fender flanges and permanently connected thereto.

23. In a fender structure, a longitudinally 95 curved fender, a fender apron, said fender and apron having their outer surfaces substantially continuous and having abutting flanges bent away from said outer surfaces, extending along the line of longitudinal 100 curvature and permanently connected together, and a support for said fender and apron.

24. In a fender structure, a fender curved both longitudinally and transversely, a 105 fender apron, said fender and apron having their outer surfaces substantially continuous and having abutting flanges bent away from said outer surfaces and permanently connected together, and a sheet metal 110 flanged channel bracket connected to and supporting said fender and said apron, and shaped substantially to the transverse contour of said parts.

25. In a fender structure, a fender, a 115 fender apron, a sheet metal flanged channel bracket connected to and supporting said fender and said apron, a sheet metal lamp bracket having a flanged base and located opposite to said supporting bracket upon the 120 upper side of said apron, and connections between said parts.

26. In a fender structure, a fender apron, a flanged sheet metal channel bracket having its flanges connected to and supporting 125 said fender and apron, a sheet metal lamp bracket having an elongated flanged base extending transversely to the apron and shaped to the transverse contour thereof, said bracket being located upon said apron 130

with its flanges opposed to the flanges of the channel bracket, and connections whereby said parts form a unitary structure.

27. In a fender structure, a fender, a fender apron, a channel bracket connected to and supporting said fender and said apron, a lamp bracket located opposite to said supporting bracket upon the upper side of said apron, said apron having an opening therethrough whereby said lamp bracket communicates with the channel in said channel bracket, and connections between said parts.

28. In a fender structure, a transversely curved sheet metal fender, a fender apron, said fender and apron being permanently connected together, a sheet metal channel bracket having flanges along its open side shaped so that said flanges follow the transverse contour of said fender and apron, except in the region of the connected flanges, said bracket bridging said connection.

29. In a fender structure, a fender having integral lateral flanges, a fender apron having a flange engaging one of the fender flanges and connected thereto, a sheet metal flanged channel bracket for supporting said fender and apron, extending transversely thereto and of decreasing channel depth as it approaches said fender, said channel tapering into the plane of the flange and said bracket being bent down at the end to abut the outer fender flange.

30. In a fender structure, a transversely curved fender having a depending flange along its outer side and a flanged channel bracket supporting said fender, said channel bracket being shaped to the transverse contour of the fender, having a channel which tapers to the plane of the bracket flanges and being bent down at its end to abut said fender flange.

31. In a fender structure for vehicles, a fender, a fender apron, said fender and

apron being permanently connected together, a sheet metal flanged channel bracket connected to and supporting said fender and said apron and shaped to the transverse contour of said parts except in the region of the connected flanges, said bracket bridging said connection, being shaped at its lowermost end to abut the vehicle frame and having a connecting strap and a reinforcing sheath.

32. In a fender structure, a fender apron and lamp bracket permanently connected together, and a supporting bracket to which said apron is also permanently connected, said lamp bracket being opposed to said supporting bracket.

33. In a fender structure, a fender apron and lamp bracket welded together, and a supporting bracket to which said apron is welded, said lamp bracket being opposed to said supporting bracket.

34. A bracket adapted to support a mud guard and lamp in automobile construction embodying a pressed steel member secured at its lower end to the frame of the automobile chassis, to position it in upstanding relation thereto, said member being channeled in cross-section and provided intermediate its ends with an aperture, one end of said bracket being secured to and supporting the mud guard from the under side, and a hollow lamp supporting pillar supported by the channeled member in juxtaposition with the aperture therein, whereby the wires for the lamp may be led through the channeled member and through the aperture and pillar in concealed position to the lamp.

In witness whereof, I have hereunto subscribed my name in the presence of two witnesses.

JOSEPH LEDWINKA.
